UNITED STATES PATENT OFFICE.

AUGUST PETRIE, OF WEST ALLIS, WISCONSIN, ASSIGNOR TO MILWAUKEE STAMPING COMPANY, OF WEST ALLIS, WISCONSIN.

BAG-FASTENER.

1,082,476.

Specification of Letters Patent.

Patented Dec. 23, 1913.

Application filed October 23, 1913. Serial No. 796,801.

To all whom it may concern:

Be it known that I, AUGUST PETRIE, a citizen of the United States, residing at West Allis, county of Milwaukee, and State of Wisconsin, have invented new and useful Improvements in Bag-Fasteners, of which the following is a specification.

My invention relates to improvements in that class of bag fasteners in which a vertical locking member is rigidly affixed to a horizontal plate, which plate is pivotally connected to the over-lapping frame member of the bag by a hinge and in which the locking mechanism is adapted to be thrown into and out of locking engagement with a retaining catch by turning said horizontal plate on its supporting hinge.

I am aware of the fact that the locking member of a bag fastener has previously been connected to the over-lapping frame member of such bag by a hinge pin, which pin extends through the inclosing walls of such locking member, also that a spring plate adapted to hold the locking member in its locked and unlocked position has previously been connected with such inclosure by one or more rivets.

The object of my present invention is, therefore, among other things, to so improve and simplify the construction of the locking mechanism that the same may be made quicker and better and at a less expense than bag fasteners of this class as heretofore constructed.

My invention is further explained by reference to the accompanying drawings in which—

Figure 1 represents a side view in vertical section of the locking mechanism secured to the frame members of a traveling bag. Fig. 2 is a transverse section drawn on line $x-x$ of Fig. 1 as the same would appear looking in the direction of the arrows in Fig. 1. Fig. 3 is a transverse section drawn on line $y-y$ also looking in the direction indicated by the arrows in said Fig. 1. Fig. 4 is a bottom view of the device removed from the bag frame. Fig. 5 is a vertical section of the device in process of construction removed from the bag frame. Fig. 6 is a similar view to that shown in Fig. 5 showing the hinge plate pivotally secured in place, and Fig. 7 is a perspective view of the hinge plate shown in Figs. 1, 5 and 6 removed from the other co-operating parts.

Like parts are identified by the same reference numerals throughout the several views.

1 represents the under-lapping frame member which is provided with a retaining bracket 2, which bracket is rigidly connected with said frame member by the rivet 3.

4 represents the over-lapping frame member which is provided with slots 5, 5 for the reception of the fastening lugs 6, 6 and 65 with a slot 7 for the reception of the vertical locking member 8. The vertical locking member 8 is rigidly connected with the hinge plate 9 by a plurality of lugs 10, 10 which are upset or otherwise secured in the apertures 11, 11 of said hinge plate.

12 is a metallic box which serves as a means of supporting the locking mechanism upon and securing it to the over-lapping frame member 4, said box 12 being provided 75 with a pair of lugs 6, 6, as previously described, by which the same is rigidly and permanently secured to the over-lapping member 4, as shown in Fig. 1.

It will be understood that the lugs 6, 6 are 80 first formed in alinement with the end members 13 of said box so that when attached to the over-lapping members 4 they are inserted through the apertures 5 when they are turned back against the under surface of 85 said frame member, as shown in said Fig. 1, whereby said box is permanently secured in place. The hinge plate 9 is connected with the respective vertical sides of the box 12 by the hinge pin 14. Heretofore it has been 90

common in this class of fasteners to extend the hinge pin 14 through the vertical walls 15, 15 of the box. By my construction, however, the ends of the hinge pin 14 terminate within the box and said ends are rigidly 95 and securely fastened to the hinge plate 9 by and between a pair of lugs 16. The lugs 16 are formed integrally with the hinge plate 9 and said plate and lugs are formed of flexible metal which permits of said lugs 100 being bent around said hinge pin, as shown in Figs. 1 and 6. The hinge plate 9 is also provided with a central lug 17 which is adapted to bear against the spring plate 18, whereby the locking member 8 is securely 105 retained in both its locked and unlocked position, as shown in Fig. 1 and as indicated by dotted lines in said figure. When the vertical locking member 8 is in its locked position, as shown in Fig. 1, the spring plate 110

- 2
- 18 is adapted to bear against the extreme end of said central lug 17, as shown in Figs. 1 and 6. When, however, the vertical locking member 8 is thrown back and brought out of its locking position, as indicated by dotted lines in Fig. 1, the spring plate 18 is adapted to bear against the side of said lug 17 thereby serving to hold the vertical locking member 8 in its open position.
- 10 The hinge pin 14 is preferably provided at its respective ends with semi-circular bearing collars 22, 22, which are interposed between said hinge pin and the opposing surface of the box 12, said bearing collars 15 serving to form a uniform bearing surface for said hinge pin, whereby it is free to turn in its bearings with a minimum resistance.
- It will be understood that the box 12 is formed of flexible sheet metal adapted to be 20 struck up with dies and when so formed it is provided with a semi-cylindrical member 19, shown in Figs. 1, 5 and 6, for the reception of the ends of the hinge pin 14. The spring 18 is provided with a longitudinal slot 20.
- 25 The slot 20 is adapted to be placed over and around the vertical locking plate 8 when the lug 21 is inserted through the slot 20 and turned back against the under side of said spring, as shown in Figs. 1 and 4, whereby 30 said spring 18 is securely retained in place.
- It will, of course, be understood that the over-lapping frame member 4 is secured to the under-lapping frame member 1 by bringing the hinge plate 9 to the horizontal 35 position shown in Fig. 1, whereby the vertical locking member 8 is caused to engage the bracket 2 of the under-lapping frame member. It will also be understood that the bag is unlocked by a reverse movement of 40 said hinge plate 9.
- Having thus described my invention what I claim as new and desire to secure by Letters Patent is—
1. In a bag lock of the described class 45 comprising a hinge plate, a vertical locking member affixed to said plate and a supporting box affixed to the over-lapping frame
- member of the bag;—a hinge pin secured to said hinge plate and having its respective ends terminating within the vertical walls 50 of said supporting box, a vertical locking member secured to said hinge plate, a spring plate adapted to hold said hinge plate in its bearings in said supporting box, means for securing said spring plate to said supporting box against the retaining bearings of said hinge plate and means for securing said supporting box to the over-lapping frame member of the bag.
2. A bag lock of the described class comprising a supporting box affixed to the over-lapping member of a bag frame, a spring retaining lug formed integral with said box, a plate hinged to said supporting box, a locking member affixed to said hinge plate, 60 a spring plate provided with a longitudinal slot for the reception of said locking member, a retaining lug, said lug being inserted through said slot and turned back against the under side of said spring plate, said lug 65 being adapted to retain said spring plate in yielding contact with the retaining lugs of said hinged plate.
3. In a bag lock of the described class comprising a hinge plate, a vertical locking 70 member affixed to said plate and a supporting box affixed to the over-lapping frame member of the bag, a hinge pin, a semi-circular bearing plate located beneath the respective ends of said hinge pin, a hinge plate 75 secured to said pin and a locking member secured to said hinge plate, a spring plate secured to said supporting box and adapted to bear against one end of said hinge plate, means for securing said spring plate in contact with said box and means for securing said box to the over-lapping frame member 80 of the bag.
- In testimony whereof I affix my signature in the presence of two witnesses.
- AUGUST PETRIE.
